APPARATUS FOR CONTROLLING THE PASSAGE OF WIRE THROUGH A SAND PAN

Charles D. Johnson, Worcester, Mass., assignor to Johnson Steel & Wire Company, Inc., Worcester, Mass., a corporation of Massachusetts

Application April 22, 1949, Serial No. 88,922

7 Claims. (Cl. 51—20)

1

The present invention relates to apparatus for controlling the passage of wire through a sand pan, such as is commonly employed for cleaning the surface of moving wire after it leaves a bath of molten metal, in the course of processing the wire. The object of the invention is to provide improved apparatus of the above-indicated character, which will effectively prevent the accumulation, or solidification, of the bath metal within the sand to such an extent that some of the metal will be pulled along with the wire as the latter leaves the pan.

The above and other advantageous features of my invention will hereinafter more fully appear from the following description, with reference to the accompanying drawings, in which—

Fig. 1 is a diagrammatic view illustrating the apparatus of the present invention as applied to a sand pan which is employed in connection with the heat treatment of wire.

Fig. 2 is a plan view, on an enlarged scale, of the sand pan shown in Fig. 1, with its associated wire lifting mechanism.

Fig. 3 is a longitudinal sectional view through the sand pan, along the line 3—3 of Fig. 2, with the lower portion of the mechanism in end elevation.

Fig. 4 is a vertical sectional view along the line 4—4 of Fig. 2, looking in the direction of the arrows.

Referring first to Fig. 1, the apparatus of the present invention is shown, for purposes of illustration, as being applied to a sand pan P that is employed in connection with a conventional arrangement for heat treating wire, wherein wire W is moved through a receptacle 1 containing a bath 2 of molten lead, in the direction of the arrow. The bath 2 is maintained at the desired temperature for heat treating the wire W, usually from 1500° to 2000° F., at which temperature the lead of the bath 2 is in an extremely fluid condition. Upon leaving the receptacle 1, the heated wire W passes through a second receptacle 3 also containing a lead bath 4 maintained at a temperature much lower than the temperature of the bath 2, and usually in the neighborhood of from 500° to 1000° F.

The purpose of the second bath 4 is to rapidly quench or cool the wire W, and reduce its temperature to a point where the wire W can be subsequently handled. For best results, the quenching bath 4 is in a semifluid or mushy state, so that heat is rapidly extracted from the wire as it passes through the bath, to give the desired quenching effect and thereby obtain the desired

physical properties in the wire, due to rapid heating and cooling of the same. As the wire W leaves the quenching bath 4, it passes upwardly beneath a sinker 5 into the pan P which contains coarse sand S, with the bottom 6 of the pan P being inclined upwardly from one end of the quenching bath receptacle 3.

The quenched wire W is moved through the sand pan P over a roll 7 mounted beyond the pan, 10 and in passing through the sand S, any lead adhering to the wire W tends to be removed by the scraping action of the particles of sand S, so that the wire W will leave the roll 7 in a relatively clean condition, with substantially no lead adhering thereto. As the lead is removed from the wire W by the scraping action of the sand S, it tends to flow back into the receptacle 3 because of the 15 downward inclination of the bottom 6 of the pan P, the lower end of which overhangs the right-hand end wall 3a of the receptacle 3. However, it has been found that lead removed from the wire W at any considerable distance from the receptacle 3 will have cooled to such an extent that it will not flow back freely through the sand 20 S; as a result of which, cooled lead will tend to solidify and accumulate around the wire W in a more or less solid mass. When the lead does collect at any one point, due to continued passage of the wire W, the sand S in the pan P is no longer 25 capable of cleaning the wire thoroughly, so that the cooled wire W coming from the roll 7 will exhibit streaks of lead, or have separate particles of lead adhering thereto.

The above-described effect is known as "lead 30 pulling," and when the effect becomes very pronounced, the only way in which it can be overcome is to renew the sand S in the pan P, in order to get rid of the accumulation of lead therein, or to manually agitate the sand where the lead has 35 gathered, by means of a hand tool. Therefore, when "lead pulling" occurs, it has been heretofore necessary to either interrupt the heat treating process while the sand S is being renewed in the pan P, or to run the risk of breaking or snarling the moving wire while agitating the sand where the lead has gathered.

As previously pointed out, the object of the present invention is to provide means for positively preventing the gathering of lead at any one point in the sand pan P by bodily shifting the wire W as it moves through the sand S. As will later appear, such shifting of the wire W has the effect of continuously bringing fresh particles of sand in contact with the moving wire 55 W, so that the lead never has a chance to gather

at any one point, and will flow freely back into the receptacle 3 as it is removed from the wire W by the scraping action of the particles of sand S.

As best shown in Figs. 2 and 4, the arrangement for shifting the wire W consists of a bar 8 extending across the open top of the sand pan P near its upper end, with the bar 8 providing downwardly extending arms 9 for rotatably supporting between them a roll 10 which is disposed just above the bottom 6 of the pan P when the parts of the mechanism occupy their full-line positions. The roll 10 provides a number of grooves 11 extending around the surface thereof, which grooves 11 are adapted to receive any desired number of wires W that are being subjected to heat treatment by passage through the lead baths 2 and 4, it being customary to process a number of wires simultaneously while maintaining the wires in parallel relation in passing through the baths and through the sand pan P, as shown in Fig. 2.

The bar 8 extends at either end beyond the longitudinal sides of the pan P, and the bar 8 is attached at its ends to slides 12 that are vertically movable in suitable tracks 13 mounted on frame members F which support the sand pan P in an inclined position above the end wall 3a of the lead receptacle 3. Each slide 12 carries a roll 14 bearing on the surface of a cam 15, in the form of a circular disk, that is mounted eccentrically on a shaft 16 that extends beneath the pan P and is rotatably mounted in bearings 17 provided on the inside of the tracks 13. Therefore, the entire assembly of parts represented by the roll 10, the bar 8, and the slides 12, is adapted to be supported by the rolls 14 bearing on the cams 15, with the slides 12 being guided in the tracks 13 by pins 18 movable in slots 19 provided in the slides 12.

The cams 15 are rigidly secured to the shaft 16 by means of hubs 15a, and the shaft 16, with the cams 15, is rotatably driven from a source of power, such as an electric motor 20. Preferably, the shaft 16 is driven at a relatively low speed, i. e., from 1 to 5 revolutions per minute, through suitable reduction gearing 21 between the motor 20 and the shaft 16. When the shaft 16 is so rotated, the slides 12 carrying the bar 8 and the roll 10, will have an up and down reciprocatory movement imparted thereto for each complete revolution of the cams 15 with which the rolls 14 are continuously in engagement.

With the parts occupying the full-line positions of Figs. 3 and 4, all of the wires W are moving through the sand S in the pan P in a substantially straight line between the roll 7 and the point where the wires W leave the quenching bath beneath the right-hand sinker 5 which is in the form of a grooved bar that is submerged beneath the surface of the lead bath 2. At the particular moment when the rolls 14 on the slides 12 occupy their lowermost position, the wires W are traveling through the sand S in the pan P in a direction which is slightly inclined upwardly with respect to the bottom 6 of the pan P. However, as the cams 15 rotate with the shaft 16 from the position of Fig. 3, the slides 12 and bar 8 will slowly move upwardly to cause the roll 10 to lift all of the wires W, with all of the wires being shifted bodily within the sand S until they reach the dotted-line position of Fig. 3 which corresponds to the upper limit of the movement of the slides 12 by the cams 15. As

soon as the wires W reach their dotted-line position, they will immediately start to move downwardly through the sand to the full-line position near the bottom 6 of the pan P, and obviously this shifting movement of the wires through the sand will continue at a slow measured rate as long as the shaft 16 is driven by the motor 20.

It will be apparent from a consideration of Fig. 3, that the amplitude of the shifting movement of a wire W with reference to a fixed point represented by the sinker 5, increases in direct proportion to the distance between the sinker 5 and the wire-lifting roll 10. Consequently, while the shifting of the wire is very slight where it leaves the sinker 5 and enters the sand pan P, with the lead in a soft condition, the shifting increases progressively toward the roll 7, so that by the time the lead starts to cool appreciably, it has reached a zone wherein shifting of the wire W and consequent agitation of the sand S is at a maximum.

As a result of the above-described bodily shifting of all of the wires W simultaneously with their passage through the sand pan P, it has been found that the "lead pulling" previously referred to, is eliminated, and that the wires W will pass off the roll 7 substantially free of lead. This results in an extremely uniform production of clean wire, without requiring any manual operations such as have been heretofore involved in changing the sand S in the pan P, or in agitating the sand S by means of a hand tool, with the chance of breaking or snarling the moving wire.

I claim:

1. Apparatus of the class described comprising in combination, a sand pan having one end thereof located adjacent to a bath of molten metal, means for moving wire lengthwise through the sand in said pan after leaving said metal bath, and means for laterally shifting said wire within the sand simultaneously with lengthwise movement of the wire therethrough.

2. Apparatus of the class described comprising in combination, a sand pan having one end thereof located adjacent to a bath of molten metal, means for moving wire lengthwise through the sand in said pan after leaving said metal bath, means for supporting the wire independently of the pan at the end opposite to said metal bath, and means for changing the position of said wire supporting means with respect to the bottom of the pan, as the wire moves lengthwise through the sand therein.

3. Apparatus of the class described comprising in combination, a sand pan having one end thereof located adjacent to a bath of molten metal, means for moving wire lengthwise through the sand in said pan after leaving said metal bath, a member extending transversely across said pan over which the wire passes in its travel through the sand, and means for imparting a reciprocatory movement to said member for shifting the wire within the sand simultaneously with its lengthwise travel therethrough.

4. Apparatus of the class described comprising in combination, a sand pan having one end thereof located adjacent to a bath of molten metal, means for moving wire lengthwise through the sand in said pan after leaving said metal bath, a member extending transversely across the pan at the end opposite to the metal bath, for freely supporting the wire adjacent to where it leaves said pan, and means for moving said wire sup-

porting member up and down with respect to the bottom of the pan simultaneously with lengthwise movement of the wire over said member.

5. In apparatus for controlling the passage of wire through a stationary pan containing a mass of sand, a member over which the wire passes while embedded in the sand, and means for imparting a reciprocatory movement to said member for laterally shifting said wire within the sand simultaneously with its lengthwise movement therethrough.

6. In apparatus for controlling the passage of wire through a stationary pan containing a mass of sand, a member extending above the open top of said pan for supporting a guide over which the wire passes while embedded in the sand in its lengthwise travel through the pan, and means for imparting a reciprocatory movement to said member for raising and lowering said wire guide within the sand simultaneously with the lengthwise passage of the wire over said guide.

7. In apparatus for controlling the passage of wire through a stationary pan containing a mass

of sand, means for supporting said pan with its bottom inclined with respect to the horizontal, a rotatably driven shaft extending under the raised end of said pan, a cam mounted on said shaft, a slide extending vertically at one side of said pan for receiving a reciprocatory movement from rotation of the cam on said shaft, a member carried by said slide extending across the open top of said pan and a wire guide supported by said 10 cross member below the surface of the sand for laterally shifting said wire within the sand simultaneously with its lengthwise movement therethrough.
